UNITED STATES PATENT OFFICE.

JOHN J. NORMAN, OF CHICAGO, ILLINOIS, ASSIGNOR TO THE J. J. NORMAN COMPANY, OF SAME PLACE.

GAS AND OIL ENGINE.

SPECIFICATION forming part of Letters Patent No. 548,922, dated October 29, 1895.

Application filed November 16, 1894. Serial No. 529,071. (No model.)

To all whom it may concern:

Be it known that I, JOHN J. NORMAN, a citizen of the United States, residing at Chicago, county of Cook, and State of Illinois, have invented certain new and useful Improvements in Gas and Oil Engines, which are fully set forth in the following specification, reference being had to the accompanying drawings, forming a part thereof, in which—

10 Figure 1 is a partly-sectional side elevation of my improved engine, the base or standard or fly-wheel and the lighting-chamber being partly broken away, and the cylinder also being broken away and shown in axial section 15 at the exhaust-port. Fig. 2 is a vertical section, on a reduced scale, at the line 2 2 on Fig. 1. Fig. 3 is a detail section, on a still larger scale, at the same plane as Fig. 2, of the governing mechanism and the gas-inlet and 20 screening-chamber. Fig. 4 is a section at the line 4 4 on Fig. 3. Fig. 5 is a detail section transversely through the cylinder and its jacket at the exhaust-port and designed especially to show the latter.

25 This engine is illustrated as designed to operate in upright position—that is, the stroke of the piston being vertical. It comprises, therefore, a base A and the standard or frame B, supported thereon, having in the lower 30 part bearings B' B' for the main crank-shaft or fly-wheel shaft C and in the upper part the cylinder B² and its jacket B²⁰.

c c represent fly-wheels on the shaft C; c¹¹, a band-wheel.

35 The double crank C' C' between the bearings B' B' and the pitman D on the crank-wrist c' are of usual construction.

40 E is the piston, which is a hollow cylinder with one head at the upper end, formed, however, with bosses E' E', substantially in transverse line with the center of gravity of the piston, adapted to give firm seat and means of fastening to the wrist-pin E², on which the upper end of the pitman D is pivoted and at 45 which it is connected to the piston. The wrist-pin E² is held tightly in place in bosses E' E' by set-screws e' e', and it is provided with a groove E²⁰, extending longitudinally in its upper side, the bottom of the groove sloping 50 from the surface of the pin to the full depth of the groove, which is attained at the

vertical plane of the inner end of the boss at that side of the cylinder, the groove thence extending of uniform depth across the bearing of the pitman-wrist and terminating at 55 the farther side of the latter. The purpose of this groove is to admit oil to the pitman-wrist, and for this purpose the boss E', at the side at which the groove in the pin commences, has a corresponding groove E¹⁰, which 60 faces and supplements the sloping portion of the groove E²⁰ and with the latter constitutes a duct leading through the boss to the surface of the cylinder. At the point in the length of the cylinder opposite which the outer end 65 of this duct stands when the crank is passing the center at the lower limit of the stroke the cylinder is provided with an oil-duct b², formed in a post or interior boss B²¹, which extends across the chamber b²⁰ of the jacket B²⁰, and 70 an oil-cup B²² is connected to this duct at the outer side, provided with any customary devices for regulating the feed of the oil. The oil fed thus to the inner surface of the cylinder will accumulate a small drop at the inner 75 end of the duct during the momentary rest of the piston at the turn of the stroke, and such drop will be picked up by the duct E¹⁰ E²⁰, whose mouth registers with the duct b² at that instant, and this drop of oil will thus be 80 taken into the groove E²⁰ into the wrist-pin E² and will oil the bearing of the pitman on said pin.

F is the main inlet-valve. It seats upwardly in the under side of the head B³ of the 85 cylinder, on the upper side of which is mounted a frame G, which supports the governing mechanism and comprises a mixing vaporizer and screening-chamber G'. Upon the head B³ there is also mounted the lighting-chamber H. This chamber consists of an upright cylinder open at the upper end and provided with the asbestos lining H', and having a tube H², closed at the upper end by a cap H²⁰ and at the lower end screwed 90 through the cap B³, having communication by way of the short duct b² with the upper end of the cylinder B² above the limit of the travel of the piston—that is to say, communicating with the portion of the cylinder which constitutes the compression and explosion chamber wherein the gas is compressed and ex- 95 100

ploded to develop the power. The cylinder H has a lateral hollow boss H³ at the lower end, and the lighting-jet tube J is suitably supported upon the cylinder with its open end presented to the open mouth of the boss, so that as the jet is thrown into the lighting-cylinder it will draw a suitable quantity of air to produce an intensely-hot flame in the cylinder H', rendering the pipe H² hot enough to cause the gas and air mixture which will be forced up into it from the explosion-chamber to be ignited at the proper time.

J' is the valve which controls the oil-jet for the lighter.

15 J² is a drip-cup which receives an initial quantity of oil to heat the lighter in the first instance to the point of vaporization of the oil admitted past the valve J'.

The oil reaches the valve J' by way of the 20 duct j³ in the boss J³, formed on the under side of the tube J, the supply-pipe being screwed into this boss at J³⁰. The oil reaches the drip-cup by way of a small duct J²⁰, which leads from the tube J at a point just beyond 25 the valve-seat down through the boss J³, avoiding the duct j³ of the latter and emerging through the downwardly-projecting boss J³¹, into which the stem of the drip-cup is screwed. The drip-cup thus serves to plug 30 the duct j³⁰, which is bored across the duct j³ into the valve-chamber j¹⁰ to complete the passage-way for the oil to the valve. The outer end of the duct j³ is permanently closed by the plug j³².

35 J¹¹ is an air-opening into the tube J, just beyond the valve J', which permits the oil or vapor jet admitted by the valve J' to take air for intermixture while it is passing through the tube J, as well as at its emergence from 40 said tube into the chamber H.

The principal supply of oil or vapor for the compression and explosion chamber is controlled by the valve K in the fitting L. This fitting L is an angle fitting having the valve 45 K inserted and seating in its horizontal arm, and having its vertical arm L' inserted downwardly through the top of the mixing and screening chamber and secured gas-tight thereinto. In this vertical arm L' there is the 50 gas or oil inlet valve L¹⁰, which seats inwardly beyond the emergence of the duct of the horizontal arm into the chamber l¹⁰ of the valve L¹⁰, and has its stem L¹¹ extending on through the said vertical arm L' of the fitting into the 55 mixing, vaporizing, and screening chamber. The latter chamber opens sideward at G¹¹, and there is attached to it at said opening a valve-chamber G¹², provided with a flap-valve g¹², seating horizontally over the inner end of the 60 downwardly-open mouth G¹³, which leads to the outer air. This valve acts, therefore, as an air-check valve, admitting the air to the chamber and tending to prevent its return outwardly. The main inlet-valve F has its 65 stem F' produced upwardly through the chamber G' and above the same, emerging therefrom through the boss G¹⁴, for purposes here-

1 inafter more fully set out. At a point within the chamber G' this stem F' has the slot f', and a short lever M, fulcrumed on the bolt m, 70 supported by the walls of the chamber, has one end adapted to enter the slot f' and the other end extending inwardly into the downwardly-protruding end of the stem L¹¹ of the valve L¹⁰. The two arms of the lever are 75 equal, and the parts are so proportioned and related in position that the valve F is seated upwardly at the same instant that the valve L¹⁰ is seated downwardly. The valve F is 80 opened solely by suction, the downward movement of the piston E in the cylinder at each alternate action producing a partial vacuum above it and causing the valve F to leave its seat and drawing in mixed air and gas from the mixing and screening chamber. The 85 valve L¹⁰, it will be seen, therefore opens more or less, exactly in proportion to the valve F, and remains open for precisely the same length of time as the valve F. The amount of oil, therefore, which is admitted or drawn 90 in at each charge is precisely proportioned to the amount of the charge—that is to say, to the amount of explosive mixture which is sucked in past the valve F. The governor mechanism is therefore contrived with a view 95 to regulating the extent to which the valve F is opened according to the speed and the demands of the work, reducing the opening as the speed increases and thereby reducing the amount of the explosive mixture drawn in 100 and the force developed by the explosion to the minimum necessary to maintain the speed without increasing it above the desired point. In this respect our invention is distinguished 105 from the ordinary construction, in which the governing is effected by shutting off entirely the supply of explosive mixture whenever the speed passes a certain point and causing the engine to run by acquired momentum only 110 through the succeeding cycle or cycles until the speed is reduced to the point requiring another impulse. This more usual mode of governing has been heretofore regarded necessary or preferable, because all attempts to graduate the supply of gas continuously according to the speed have been attended with 115 danger of producing an improper mixture when the gas-supply was reduced below or increased above a certain point. By the construction above described, however, the oil-supply being graduated perfectly in proportion to the quantity of gas used at each stroke, whether much or little, the proper mixture of the gas and air is always obtained, the variation effected by the governor being a variation 120 only in the quantity of that mixture drawn into the cylinder and exploded at each action.

For the purpose of governing the opening of the valve F, and thereby the valve L¹¹, I 125 employ a centrifugal governor, whose centrifugal balls are seen at Q' Q', and which, by connections which will presently be described, 130 operates a slide P, which plays horizontally

through a slot f^{11} in the stem F' of the valve F outside the chamber G', but within the boss G¹⁴, through which that stem emerges, the boss being horizontally apertured for the slide, as well as having vertical apertures for the stem. This slide P has a notch P', adapting it to act as a stop upon the upper shoulder f^{12} of the slot f^{11} , said shoulder being V-shaped and adapted to enter the notch through the bottom when the valve F is opened to the maximum. The notch P' has at the left hand a long sloping face p' , the other face p^{10} having a more abrupt slope, corresponding to the slope of the V-shaped shoulder f^{12} . This slide is connected to the governor by mechanism in such manner that when the governor is at rest the slide stands in the position shown in Fig. 4, holding the valve F closed. Under slow motion the point of the shoulder f^{12} stands in line with the bottom of the notch P' and permits the valve F to be opened to the maximum. As the speed increases, the slide is pushed to the right and the range of movement of the valve is diminished until at the maximum speed the top of the long slope p' is under the point of the shoulder at f^{12} and no opening of the valve is possible. The valve F is held normally seated by a spring F², coiled around its stem above the boss G¹⁴ and stopped by a nut f^{13} , screwed onto the upper end of the stem and secured from accidental movement by a jam-nut f^{14} .

I will now describe the governor and mechanism for connecting it with the slide P. The frame G terminates at the left hand (referring to Fig. 3) in a boss G⁴, which is bored horizontally and receives the end of a horizontal stem or extension G⁴⁰, which is secured in place by a set-screw g^{40} . This stem affords bearing for the sleeve R, to which the pulley R' is made fast adjacent to the boss G⁴, and also for the sleeve S.

To the sleeve R, by means of the links Q Q, the governor-balls Q' Q' are connected, said balls being pivoted to the outer end of the links, and the flat springs Q⁸ Q⁸, rigidly secured at one end to the balls, respectively, are secured at the other ends, respectively, to the sleeve S, the links, balls, and springs constituting thus a connection between the sleeves R and S, adapting them to rotate together, but to be longitudinally movable toward and from each other. The sleeve R, however, is stopped against longitudinal movement between the annular boss g^{41} on the sleeve G⁴⁰ and the collar r, made fast to the stem at the other end of said sleeve. The sleeve S is thus adapted to move longitudinally toward and from the sleeve R as the balls depart from and approach the stem, their centrifugal force when rotating tending to cause them to depart and the springs tending to make them approach said stem.

T is a stem or shaft extending within and throughout the length of the stem G⁴⁰ and inwardly from said stem toward the chamber G', near which it terminates, and is provided

with a wide-flanged collar in two parts T' T', screwed onto the end of said stem and serving, respectively, each as the jam-nut for the other, whereby they are both secured fast.

From the wall of the chamber G' a lug G¹⁵ projects horizontally and affords the fulcrum for a lever P², whose opposite end is pivotally connected to a link P⁸, which is pivoted at p^8 to the slide P, being virtually a continuation of said slide, but jointed to it to accommodate the movement of the lever P². This lever is forked, and the collar T' T' extends between the arms of the fork, on which antifriction-rollers p^2 p^3 are journaled, facing inwardly and entering the groove or space between the flanges of the collar T' T'. A lug G¹⁶ projects up from the frame G, across the line of the slide P produced, and a thumb-screw P⁴ is screwed through this lug and secured by a jam-nut p^4 , and carries on its inner end a flanged collar P⁴⁰, which serves as a seat for one end of the spring P⁵, the other end of which is stopped upon an annular flange P³⁰, formed on the link P³. This spring and the thumb-screw P⁴, which supports one end of it, constitute a flexible extension of the slide P³ to a support in the lug G¹⁶, the flexibility of the spring serving to adapt the link to yield sufficiently to accommodate the movement of the lever P², while the spring primarily tends, reacting against compression, to force the slide P endwise outwardly—that is, to thrust it through the stem F'.

The stem or shaft T, which at the inner end is connected, as described, to the lever P², at the outer end protrudes beyond the outer end of the sleeve R and is provided with adjusting-nuts R¹⁰ R¹⁰, adapted to tighten one against the other for security, the inner one stopping on the end of the sleeve R. A cap R', apertured at the head to permit the end of the shaft T to protrude through it, covers the nuts and is screwed onto the end of the sleeve R, thus securing the sleeve rigidly, with capacity for adjustment, to the shaft T, and through the medium of the springs Q⁸ Q⁸ bringing the central shaft T into connection with the centrifugal balls, so that as the balls move outwardly and inwardly in obedience to the centrifugal force and the retracting power of the springs the sleeve moves the shaft inwardly and outwardly and by means of the lever P² causes it to move the slide P. A belt W, which is driven by a pulley W' on the main crank-shaft outside the bearing of the latter in the frame, passes around the pulley R' and rotates that pulley and the sleeve R, sleeve S, and shaft T, giving centrifugal motion to the balls Q', such rotary movement being consistent with the reciprocating motion of the shaft T, above described, in view of its connection with the lever P, which is effected by means of the rollers p^3 on the fork-arms of the lever P², engaged between the flanges of the collar T' T', so that while moving endwise in obedience to the reciprocating force of the balls and the retraction of the springs Q⁸ the rod

nevertheless freely revolves between the fork-arms of the lever, which its endwise movement actuates. Scrutiny of this structure will make it evident that the more rapid the 5 rotary motion of the governor-balls the farther the sleeve P will be pushed through the stem F', and assuming the parts adjusted so that at the slowest motion the bottom of the notch P' is in line with the point of the shoulder 10 f¹², permitting the longest movement and widest opening of valve, it will be seen that the opening of the valve is diminished as the speed increases and the slide is thrust farther through the valve-stem. When, however, 15 the governor comes to rest and the balls assume position nearest together, the slide P is pulled back so far that the point of the shoulder f¹² passes over the slope P¹⁰ of the notch P', and the valve is held shut precisely as at 20 the most rapid speed of the governor, but by the engagement of the shoulder at the opposite side of the notch. The same effect—to wit, closing the valve F by the arrest of the shoulder f¹² in the position shown in Fig. 4— 25 will result from any action that stops the governor, such as breaking of the belt. A like effect will be produced by the breaking of the spring P⁵, but by the breaking of the springs Q³, the shaft T being freed from the 30 action both of the balls and of said springs, the spring P⁵ would alone control the position of the slide and would force it to the opposite limit, and thus close the valve and stop the engine.

35 In order to start this engine, the shaft T will be pushed in by hand enough to permit the valve to open, and the latch Q⁴, which is pivoted to the inner side of the boss G⁴, will be thrown over between the end of the stem 40 G⁴⁰ and the stop-collar T⁴, which is secured on the rod T in position to stop ordinarily against the end of the stem G⁴⁰ when the slide is drawn out to extreme position, as shown in Fig. 4, the thickness of the latch being sufficient 45 simply to hold the slide with the bottom of the notch P' in line with the point of the shoulder f¹², to permit the valve F to open fully. After the engine has acquired a speed of about fifty revolutions per minute, the latch 50 will be thrown back and the subsequent operation will be controlled entirely by the governor, as described.

This engine is designed to have its principal and ordinary exhaust through a port B²¹, located midway in the travel of the piston from the point at which it receives the impulse of the explosion to that point—that is to say, at the limit of its outward stroke. Such exhaust-port is shown in section in Fig. 55 5, the inner wall or wall of the cylinder proper being perforated or provided with a number of apertures p²¹, opening through it into a hollow pillow or web, which at that point bridges the jacket-chamber and has the said 60 exteriorly-open port B²¹ for the exhaust-pipe B⁶. When no other provision is made for exhausting the gas after explosion and expan-

sion, the return stroke of the piston, after it passes such exhaust-port, finds the cylinder occupied with burned gas at somewhere near 70 atmospheric tension, which it would be obliged to compress in completing its stroke, with a loss of power not only because of the power necessary to effect such compression, but also because that quantity of inert gas 75 in the chamber impairs the efficiency of the next charge of gas for explosion. To avoid this defect I provide a relief-port at the upper end of the cylinder, as shown at b⁴⁰. A valve - chamber B⁴ is secured to the outer 80 side of the cylinder with its cavity communicating with this relief-port. The valve X opens inward and its stem X' extends out through the body of the valve-chamber and down alongside the cylinder parallel therewith 85 through the bearings provided for it at B⁵ and B⁶. Below the latter there is secured to it a forked collar X², having journaled between its fork-fingers a roll X²⁰, which is adapted to bear upon the periphery of a cam Y' on the 90 hub of a gear Y, having double the number of teeth of the gear y, said smaller gear being fixed upon the main crank-shaft adjacent to its bearing in the frame. The spring X³, coiled around the stem X' below the bearing B⁵, is 95 stopped by the nut X³⁰. This spring tends to seat the valve and is compressed when the valve is forced open. It will be seen that the cam Y' on the gear Y will make one revolution for each two revolutions of the main 100 crank-shaft, and the cam is so adjusted that it pushes the rod up and opens the valve at the point in each alternate revolution of the crank-shaft which corresponds to the travel of the piston after it passes the exhaust-port 105 in its return stroke after each explosion and holds said relief-valve open long enough to permit the piston to complete such return stroke, and thereby force out the inert gas, which it would otherwise be compelled to 110 compress. In the other alternate stroke of the piston, during which a charge of gas is compressed preparatory to explosion, the relief-valve is closed and will be held firmly seated not only by the spring X³, but also by 115 the pressure of the gas within the cylinder which is being thus compressed by the piston's travel.

In order to adapt the engine to be run in either direction, which is rendered possible 120 by the location of the exhaust-port at the middle of the travel or end of the downstroke, the cam Y' may be adapted to be adjusted ninety degrees. The means shown for effecting such adjustment is the detachment of the 125 cam from the hub and reattachment at a point ninety degrees around from its first position, suitable screw-holes being provided for securing it by preference at either position. On a stem X' above the bearing B⁵ a collar 130 X¹⁰ is secured in such position that it does not prevent the valve from seating, but so near said guide-bearing that a latch X⁴, which is pivoted to the cylinder, being turned over

- between the bearing and the collar when the valve is open, will prevent it from seating. The purpose of this is to hold the relief-valve open when the engine is being started by hand, as is the customary manner, so that several revolutions may be made and sufficient momentum acquired to compress the first charge of gas before such charge is drawn in, the relief-port permitting free ingress and egress of air so long as the valve is open, preventing the piston from opening the gas-inlet valve and from taking any gas therethrough or from compressing any gas that may be in the cylinder, and so preventing any explosion until, sufficient momentum being thus obtained and the relief-valve being closed by withdrawing the latch, a charge which will then be taken can be compressed and exploded.
- 20 It will be understood that the engine above described operates after the manner of what are commonly called "four-cycle" engines—that is, that the piston makes one downstroke to draw in a charge, one upstroke to compress it and explode it, a second downstroke under the impulse of the explosion, and a second upstroke to empty the cylinder of the remnant of the exhaust-gas, an impulse being received thus once in each alternate revolution of the crank-shaft. The lighting-chamber, having the interior tube adapted to be kept at glowing heat for the purpose of igniting the charge, is located at a distance from the upper end of the cylinder, ascertained by experience to be sufficient to permit the gas to be compressed sufficiently to be ignited by red heat only of the pipe, the life of which is thereby rendered much longer than if, as in many engines, it were necessary to maintain it at white heat.
- 30 Uniformity in respect to the point of the stroke at which the explosion will occur is greatly assisted by the fact that the air-inlet opens downward close to the cylinder, which is hot, so that the air which is drawn in through it comes from the immediate vicinity of the cylinder and is thereby warm and dry, or at least more uniformly dry than it would otherwise be throughout varying conditions of atmosphere.
- 50 I claim—
1. In a gas engine in combination with the cylinder and its main inlet valve, a centrifugal governor and connections therewith to the main inlet valve by which the governor controls the extent of the opening of such valve, the oil inlet valve and lever connections from the main inlet valve to the oil inlet valve by which the latter is opened whenever the former opens and proportionately to the opening of the former, substantially as set forth.
  2. In a gas engine in combination with the cylinder the main inlet valve adapted to be opened solely by the suction produced by the withdrawal of the piston, the oil inlet valve and lever connections from the main inlet valve to the oil inlet valve by which the latter is in every instance opened when the former
- opens, said connections being such as to make the openings of said valves in all instances bear the same ratio to each other, substantially as set forth.
3. In a gas engine in combination with the cylinder and the main inlet valve adapted to be opened solely by the suction caused by the withdrawal of the piston, a stop to limit the extent of the opening of said valve, a centrifugal governor and connections therewith to such stop adapted to move the latter to determine the extent of the opening of the main inlet valve according to the speed of the governor, substantially as set forth.
4. In a gas engine in combination with the cylinder and the main inlet valve thereof, the oil inlet valve and connections between said valves by which the opening of the former in every instance opens the latter, said connections being such as to cause the openings of said valves in all instances to bear the same ratio to each other, a governor and connections therewith to the main inlet valve adapted to control the extent of the opening of said valve and thereby the extent of the opening of the oil inlet valve, said connections being adapted to hold said valves widest open at a predetermined minimum speed of the governor, and to diminish the opening as the speed increases or diminishes from such minimum, substantially as set forth.
5. In a gas engine in combination with the cylinder and the main inlet valve thereof adapted to be opened solely by the suction caused by the withdrawal of the piston, a stop to limit its opening, a centrifugal governor and connections from the same to the stop adapted to hold the latter at the position corresponding to the widest opening of the valve when the governor has a certain slow speed and to move it to the position which shall hold the valve closed when the motion ceases, substantially as set forth.
6. In a gas engine, in combination substantially as set forth, the cylinder, the mixing or vaporizing chamber, the main inlet valve controlling communication between the two seating yieldingly and opening inwardly with respect to the cylinder, and having its stem extending through and protruding from the vaporizing or mixing chamber, said stem having the abutment or shoulder f^{12} ; a slide P, adapted to operate transversely with respect to the valve stem, and having an inclined edge in the path of said abutment; a centrifugal governor, and connections therewith to the slide adapted to control the position of the said inclined edge of the latter with respect to the path of travel of the abutment, whereby the stroke of the valve is reduced as the speed increases.
7. In a gas engine in combination with a cylinder and its main inlet valve and a movable stop which limits the opening of said valve, a centrifugal governor having the stem T adapted to be thrust longitudinally by the centrifugal action of the governor balls, con-

nections from said stem to said movable stop whereby the movement of the stem adjusts the stop to vary the extent of opening of the valve, said governor stem having the stop 5 collar T^4 and the latch Q^4 pivoted on the governor frame adapted to be interposed between said frame, and the stop T^4 to hold the stem T protruded, and the stop T in position to permit the valve to open regardless of the governor, substantially as set forth.

8. In a gas engine, in combination with the cylinder, the main inlet valve adapted to open inwardly with respect to said cylinder, the stem of said valve having a transverse slot 15 whose upper end constitutes an abutment; a slide adapted to be reciprocated through said slot and having a notch with sloping edges into which said abutment is adapted to enter to permit the valve to open, the valve being 20 held closed while the abutment is held entirely out of the notch; governing mechanism connected to said slide and adapted to operate it back and forth through the slot, whereby the valve is restrained from opening at the 25 position of rest and at a determined maximum speed of the governor, and its opening graduated to a maximum at an intermediate slow speed: substantially as set forth.

9. In a gas engine, in combination with the cylinder, the main inlet valve seating yieldingly and adapted to open inwardly with re-

spect to the cylinder; a slide adapted to be reciprocated transversely with respect to the stem of said valve, said slide and stem having the one an abutment and the other a face 35 obliquely transverse to the direction of reciprocation of the stem and adapted to collide with the abutment; and governing mechanism connected to and adapted to actuate the slide: substantially as set forth.

10. In a gas engine in combination with the main inlet valve thereof and a movable cam or stop whose position determines the extent to which said valve opens and adapted at a certain position to prevent the opening of the 45 valve, a centrifugal governor and connections therefrom by which it operates such movable cam or stop, the governor balls being provided with springs tending to resist their centrifugal action, and a spring connected to said cam 50 or stop tending to move the latter to the position at which it prevents the opening of the valve, substantially as and for the purpose set forth.

In testimony whereof I have hereunto set 55 my hand, in the presence of two witnesses, at Chicago, Illinois, this 13th day of November, 1894.

JOHN J. NORMAN.
